(57) **CLAIM**

I claim the ornamental design for a carrier for bottles, cans, beverages, food containers, or the like, as shown and described.

DESCRIPTION

FIG. 1 is a perspective view of one embodiment of a carrier for bottles, cans, beverages, food containers, or the like showing the new design.

FIG. 2 is a perspective view thereof from a different angle.

FIG. 3 is a front elevational view thereof.

FIG. 4 is a rear elevational view thereof.

FIG. 5 is a right side elevational view thereof.

FIG. 6 is a left side elevational view thereof.

FIG. 7 is a top view thereof.

FIG. 8 is a bottom view thereof.

FIG. 9 is a second embodiment of a carrier for bottles, cans, beverages, food containers, or the like;

FIG. 10 is a perspective view thereof;

FIG. 11 is a front elevational view thereof;

FIG. 12 is a rear elevational view thereof;

FIG. 13 is a right side elevational view thereof;

FIG. 14 is a left side elevational view thereof;

FIG. 15 is a top view thereof;

FIG. 16 is a bottom view thereof;

FIG. 17 is a perspective view of a third embodiment of a carrier for bottles, cans, beverages, food containers, or the like;

FIG. 18 is a perspective view thereof;

FIG. 19 is a front elevational view thereof;

FIG. 20 is a rear elevational view thereof;

FIG. 21 is a right side elevational view thereof;

FIG. 22 is a left side elevational view thereof;

FIG. 23 is a top view thereof;

FIG. 24 is a bottom view thereof;

FIG. 25 is a perspective view of a fourth embodiment of a carrier for bottles, cans, beverages, food containers, or the like;

FIG. 26 is a perspective view thereof;

FIG. 27 is a front elevational view thereof;

FIG. 28 is a rear elevational view thereof;

FIG. 29 is a right side elevational view thereof;

FIG. 30 is a left side elevational view thereof;

FIG. 31 is a top view thereof; and,

FIG. 32 is a bottom view thereof.

Specific features shown in broken lines do not form any part of or otherwise limit the claimed design.
